UNITED STATES PATENT OFFICE.

JOSEPH SEDLACSEK, OF BINGHAMTON, NEW YORK.

DOOR-LOCK.

1,154,271.

Specification of Letters Patent. Patented Sept. 21, 1915.

Application filed March 25, 1915. Serial No. 16,884.

To all whom it may concern:

Be it known that I, JOSEPH SEDLACSEK, a citizen of the United States, residing at Binghamton, in the county of Broome and State of New York, have invented certain new and useful Improvements in Door-Locks, of which the following is a specification.

This invention relates to certain new and useful improvements in door locks.

The primary object of this invention is the provision of a lock primarily adapted for employment upon the inner side of a room door and adapted for retaining the key operatively positioned in the lock at all times when the mechanism is in its unlocked position.

A further object of the invention is to provide a lock having a bolt throwing key readily positionable in the lock when the mechanism is locked and adapted for releasing such mechanism, the said key then being entirely restricted against removal until after the mechanism is re-locked and being removable then only upon the proper insertion and manipulation of a separate latch key.

A still further object is to provide a bolt lock with an operating key which is retained within the lock casing at all times except when the bolt is projected and at such times being readily insertible for unlocking the bolt, but being removable only after such insertion upon actuating a key engaging mechanism by means of a latch key.

With these general objects in view and others that will appear as the nature of the invention is better understood, the same consists of the novel construction, combination and arrangement of parts to be hereinafter more fully described and then claimed.

In the accompanying drawings forming part of this application and to which reference is had herein by like characters designating corresponding parts throughout the several views:—Figure 1 is a front elevation of a portion of the inner side of a door and door casing provided with the present invention, the door being illustrated as locked in its closed position. Fig. 2 is a view of

the door and lock shown therein, with the cover plate of the lock casing removed and parts being shown in section, the bolt being in its projected position and the key retained within the casing. Fig. 3 is a similar view with a portion of the cover plate in position and with the key released and positioned for removal through the key-hole. Fig. 4 is a view similar to Fig. 3 showing the key about to retract the engaging latch upon the releasing turning movement thereof. Fig. 5 is a longitudinal horizontal sectional view thereof. Fig. 6 is a perspective view of the latch key employed with the lock, and Fig. 7 is a perspective view of the safety catch.

Referring more in detail to the drawings, the door 10 is illustrated in Fig. 1 as being in its closed position and being provided with the lock casing 11 secured thereto by screws 12 and having its locking bolt 13 in locked engagement with a substantially usual form of keeper 14 mounted upon the door casing 15 and secured thereto by screws 16.

It is to be understood that the locking casing 11 is adapted as an inside lock, being positioned upon the inner side of the door and with the key-hole 17 for the insertion of the operating key 18, does not extend through the door, the key only being insertible from the inner side of the door.

The bolt 13 is longitudinally slidably mounted within the casing 11 between lugs 19 and 20 arranged at the opposite sides of the bolt, while the outer free end of the bolt is movable inwardly and outwardly through an opening 21 in the lock casing, it being understood that a cover plate 22 is provided for the casing which is removably retained in position by means of a screw 23 extending through the plate and having screw-threaded engagement with a socketed post 24 within the casing.

A tumbler 25 is positioned within the casing, being pivoted at one end upon a post 26, and having a substantially rectangular opening 27 for accommodating a lug 28 which projects from the bolt 13, which lug 28 is positionable upon opposite sides of a similar lug 29 carried by the said tumbler and projecting into the said opening, such

positions being assumed when the lock bolt is projected and retracted.

The inner end of the bolt has a stop lug 30 which engages the casing lug 19 when the bolt is projected as illustrated in Fig. 2, while a leaf spring 31 has a curved end 32 thereof engaged over a lug 33 of the tumbler, which spring is constantly positioned with its opposite end engaged with a side lug 34 of the casing.

The key 18 being insertible through the key-hole opening 17 of the front casing plate 22 and having a laterally projecting ward 35, thus positioned within the casing, may readily actuate the lock bolt after clearing the safety catch hereinafter described, the said ward entering the V-shaped notch 36 of the bolt and engaging the tumbler 25 to release the tumbler lug 29 from the bolt lug 28, then allowing a further turning of the key to inwardly retract the said bolt. After such retracting movement of the key, a further turning of the key in the same direction will be prevented by means of a post, 25 which extends through the casing adjacent the key-hole slot, and which post therefore, prevents the key from being then turned sufficiently to remove the same through the said slot 17. The key however, 30 may then be turned in the opposite direction, which necessarily projects the bolt 13 and again positions the key ward 35, as illustrated in Fig. 2.

A safety catch 38 is slidably mounted within the casing upon one side 39 thereof, being adapted to slide beneath a bridge piece 40 connecting the said side 39 and the post 24. An expansion spring 41 engages between the side 43 of the casing in which the bolt opening 21 is provided, and the adjacent end of the said catch 38 and whereby the said catch is normally positioned with its curved shoulder 42 against the side of the said post 24, with the opposite end or heel 44 of the catch slightly spaced from the key-hole opening. The insertion of the key through the key-hole opening to the position illustrated in Fig. 4, allows the key to be turned so as to engage the heel 44 of the said catch 38 and longitudinally slide the same toward the casing side 43, thus compressing the spring 41 and allowing the key ward to pass the said catch and thereafter the key may be turned for retracting the bolt and again re-turned for again projecting the bolt. Upon such re-turning of the key ward, the same will engage the inner face of the catch 38 after leaving its operative engagement with the cut-out portion 36 of the bolt and the key will thus be prevented from withdrawal from the casing. Rack teeth 45 are provided upon the inner surface of the catch 38 and are adapted to be engaged by the prongs 46 upon the operative end of a latch key 47 when such key is

inserted through a circular key-hole 48 in the front plate 22. When the key 18 is in the position illustrated in Fig. 2 therefore, the latch key 47 may be inserted through the key-hole 48 and upon engaging the teeth 45 of the catch, a turning of such latch key will retract the said catch sufficiently to allow the key ward 35 to pass the key-heel 44. From this arrangement it will be seen that when the key is in the lock, the same will at all times be prevented against removal therefrom when the bolt is released by means of the post 37 and will be prevented from being removed even after the bolt is re-locked, except upon the insertion and operation of the latch key 47 and a retracting of the catch 38.

The complete operation of the device will now be apparent from the above description thereof as the manner of inserting and operatively turning the key 18 has already been herein set forth.

What I claim as new is:—

1. A lock comprising a casing having a key-hole slot, a longitudinally slidable bolt within said casing, an operating key, a stop post within said casing adjacent the said key-hole slot and at one side thereof, and a key-controlled spring-pressed stop catch within said casing adjacent the opposite side thereof.

2. A lock comprising a casing having a key-hole slot therein, a sliding bolt within the casing, a key for said lock adapted for insertion through the said slot, a key stop within said casing and positioned at one side of said slot, a spring-pressed longitudinally slidable catch at the opposite side of said slot, and operating means for the said catch.

3. A lock comprising a casing having a key-hole slot therein, a slidable bolt mounted within said casing, an operating key for the said bolt, rigid key-removal preventing means at one side of the said slot, and a key-controlled spring-pressed key removal preventing catch arranged at the other side thereof.

4. A lock comprising a casing having a key-hole slot therein, a slidable bolt mounted within said casing an operating key for the said bolt, rigid key-removal preventing means at one side of the said slot, a yieldable key-removal preventing catch arranged at the other side thereof, rack teeth upon one side of the said catch, and a latch key for the said catch having end prongs adapted for engaging the said rack teeth when positioned within the said casing.

5. A lock comprising a casing having a key-hole slot therein, an operating key for the said lock, a reciprocating bolt within the said casing, rigid means adapted for the prevention of the removal of the said key from the casing when the bolt is in its unlocked position, and a key-controlled spring-pressed

shiftable catch normally positioned in the removing path of movement of the said key when the bolt is projected.

6. In combination with a lock including a casing having an opening therein, and lock mechanism within the casing, means positioned on each side of said opening to prevent removal of said key, the means upon

one side of said opening having a rack face, and a key including projecting prongs 10 adapted to engage the rack face to shift the said means whereby the key may be withdrawn through the casing opening.

In testimony whereof I affix my signature.

JOSEPH SEDLACSEK.
